FOREIGN PATENT DOCUMENTS

CN 201582666 9/2010

Primary Examiner — Clare E Heflin(74) *Attorney, Agent, or Firm* — Frost Brown Todd LLC; Dennis S. Schell; Kevin C. Oschman(57) **CLAIM**

The ornamental design for a light fixture, as shown and described.

DESCRIPTION

FIG. 1 is a top perspective view of the new design;
 FIG. 2 is a bottom perspective view of the new design;
 FIG. 3 is a top view of the new design;
 FIG. 4 is a bottom view of the new design;
 FIG. 5 is a right side view of the new design, the left side being a mirror image;
 FIG. 6 is a front view of the new design; and,
 FIG. 7 is a rear view of the new design.
 The broken lines immediately adjacent the shaded areas represent the bounds of the claimed design while all other broken lines are directed to environment and are for illustrative purposes only; the broken lines form no part of the claimed design.

1 Claim, 6 Drawing Sheets(56)
